UNITED STATES PATENT OFFICE.

CHRIS E. PAULSON, OF BOYD, MINNESOTA.

CAR-COUPING.

SPECIFICATION forming part of Letters Patent No. 663,186, dated December 4, 1900.

Application filed June 27, 1900. Serial No. 21,837. (No model.)

To all whom it may concern:

Be it known that I, CHRIS E. PAULSON, a citizen of the United States, residing at Boyd, in the county of Lac Qui Parle and State of Minnesota, have invented new and useful Improvements in Car-Couplers, of which the following is a specification.

This invention relates to new and useful improvements in car-couplers; and its primary object is to provide a device of this character having a pin which will be automatically released by a link when inserted within a draw-head and which will engage said link and lock the same in position.

15 A further object is to provide means of peculiar construction for locking the pin in disengaged position and to provide a link of peculiar construction adapted to contact with the locking mechanism of the pin and release 20 the same when brought into the draw-head.

To these ends the invention consists in providing a draw-head having a transversely-extending recess or passage therein, within the top of which is fitted a tubular casing 25 which is arranged at a point above the passage formed in the lower portion of the draw-head. This casing is adapted to receive a pin having an annular groove therein near the upper end thereof, and this groove is adapted 30 to be engaged by a dog which projects through the slot within the casing and is secured to a shaft which is mounted within suitable ears upon the casing. This dog is held normally projected into the casing by means of a weight- 35 ed arm which is secured to the shaft, and a second arm extends downward from said shaft, at the opposite end thereof, and is provided at its lower end with an extension which is hinged thereto and which is limited in its forward movement. This extension contacts 40 with an arm of a lever which is pivoted to a side of the draw-head and is held normally in an upright position preferably by means of a weight. Within this draw-head is mounted 45 a link having trunnions, the upper one of which projects through the draw-head and engages with the end of a rod which extends upward to the top of the car to which the coupler is attached and is provided with a suitable handle. This rod is mounted in 50 brackets of any desired form and has suitable means whereby the same can be locked when

turned to a desired position. This link is of sufficient length to extend beyond the outer end of the draw-head and is provided at its 55 end with an opening for the reception of the coupling-pin of the draw-head into which it is inserted in coupling. A laterally-extending arm is provided adjacent to this opening and is adapted to engage a lever which is pivoted to the side of the receiving draw-head, thereby releasing the coupling-pin, as will be hereinafter more fully described.

The invention also consists in the further novel construction and combination of parts 60 hereinabove more fully described and claimed and illustrated in the accompanying drawings, showing the preferred form of my invention, and in which—

Figure 1 is a perspective view of the device 70 applied to a car. Fig. 2 is a central longitudinal section through the draw-head. Fig. 3 is a plan view thereof, showing in dotted lines the link swung at right angles to the draw-head. Fig. 4 is a perspective view of the locking-dog and its attachments. Fig. 5 is a rear elevation of the pin-receiving casing. Fig. 6 is a perspective view of the locking device for the link-rod, and Fig. 7 is a perspective view 75 of a link detached.

Referring to said figures by numerals of reference, 1 is a draw-head of any desired material and having a transversely-extending horizontal passage or slot 2 therein. This draw-head may be secured to a beam 3 in any desired 85 manner, as by providing a recess 4 therein, for the reception of the beam and passing bolts 5 therethrough. The upper wall of the passage 2 is provided with a threaded aperture 6 for the reception of the end of a cylindrical casing 7. This casing is provided in its rear face with a slot 8, and an ear 9 projects from said casing at each side of the slot. A passage 10 is formed within the lower wall 90 of the recess 2 and is in alignment with the interior of the casing 7. This passage is adapted to receive a pin 11, which is normally held suspended within the casing 7 by a dog 12, which engages an annular groove 13, formed within said pin near the upper end thereof. 100 This dog is secured to a shaft 14, which is mounted in the ears 9, and an arm 15 extends forward therefrom at one end and is provided with a weight 16, as shown. The opposite end

of the shaft has a downwardly-extending arm 17, recessed at its lower end, as at 18, and within this recess is pivoted an extension 19, which is capable of moving rearwardly upon 5 said pivot, but cannot move forward out of alinement with the arm 17. This extension projects downward to a point within the path of a lever 20, which is pivoted to the side of the draw-head and is provided with a weight 10 21 at the lower end thereof.

Mounted within the passage 2 of the draw-head is a link 22 of peculiar construction. This link is provided at its inner end with trunnions 23 and 24, the lower one, 23, of which 15 extends into the lower wall of said passage, while the upper trunnion 24 projects through the upper wall and is provided at its end with an eye 25. This eye is adapted to receive the end of a rod 26, which extends upward to a 20 point above the top of the car to which the device is attached and is secured to said car by means of brackets, as 27. A handle 28, preferably of the form shown in Fig. 1, is secured to the upper end of this rod, and the 25 rod is squared at a point adjacent to the top of the car, as at 29, and this squared portion is normally engaged by the forked end 30 of a lever 31. This lever is journaled in a bracket 32, secured to the top of a car and is 30 provided at its inner end, preferably, with a treadle 33, as shown. This lever may be held normally in horizontal position in any desired manner, as by means of a spring 34, as shown.

A bracket 35 is secured to the front of the 35 car and supports a rod 36, which is secured to the top of the pin 11, and whereby the same may be raised out of engagement with the link.

The link 22 is provided near its free end 40 with an aperture 37, and an arm or lateral extension 38 is provided at a point adjacent to said aperture.

When it is desired to place the draw-head in condition to receive the link of a second 45 draw-head, the link of the receiving draw-head is turned into the position shown in dotted lines in Fig. 3 by means of the rod 26 and the handle 28. In order to do this, it is necessary to first depress the treadle 33, so as to 50 throw the fork 30 out of engagement with the squared portion 29. It is obvious that when this treadle is released after the link has been turned said fork will again engage the rod, and thereby hold the link in its new position. 55 The arm 38 of the similar link of the opposite draw-head upon entering the receiving draw-head will contact with the lever 21 and force the upper end thereof forward. This will, as is obvious, bear upon the extension 60 19 and force arm 17 of shaft 14 forward, thereby raising the weight 16 and swinging dog 12 outward from engagement with the coupling-pin 11. Said pin will then drop into the aperture of the link and thence into passage 65 10, securely locking the link in position, as is obvious. It will be seen that the lever 21

will be carried back by the arm 38 of the link until the upper end of said lever escapes the end of the extension 19. The dog 12 will then be thrown back into normal position by 70 the weight 16.

When it is desired to uncouple the link, the rod 36 is drawn upward, bringing the upper end of the pin 11 into contact with the dog 12 and forcing the same upward until it 75 registers with the groove 13. The dog will then swing inward into engagement with the groove and lock the pin in raised position. As the link is retracted from the draw-head the lever 20 will gradually swing backward 80 to its normal or vertical position, the upper end thereof causing the extension 19 to swing backward upon its pivot until the upper end of said lever passes the extension and returns to its normal position, as shown in Fig. 1. 85 When it is desired to project the link of this draw-head into a second draw-head of similar construction, said link is swung into the position shown in the drawings by releasing the rod 26 and receiving the same within the 90 brackets 27.

It will be seen that the position of the link can be determined at all times by the position of the handle 28.

In the foregoing description I have shown 95 the preferred form of my invention; but I do not limit myself thereto, as I am aware that modifications may be made therein without departing from the spirit or sacrificing the advantages thereof, and I therefore reserve 100 the right to make such changes and alterations as fairly fall within the scope of my invention.

Having thus fully described my invention, what I claim as new, and desire to secure by 105 Letters Patent, is—

1. The combination with a draw-head having a transversely-extending recess therein; of a cylindrical casing secured to the draw-head and communicating with said recess, a 110 pin slidably mounted within the casing and having an annular groove therein, a dog pivoted to the casing and projecting through a slot therein and adapted to engage with the groove of the pin, and a weighted arm for holding said dog normally projected into the casing.

2. The combination with a draw-head having a transversely-extending recess, of a casing secured thereto, a shaft journaled upon 120 the casing, a dog thereon adapted to project into the casing, a weighted arm to the shaft, a second arm thereto, and a weighted lever pivoted to the draw-head and projecting into the path of said arm.

3. The combination with a draw-head having a transversely-extending recess therein, of a casing secured thereto, a shaft mounted upon the casing, a dog secured to the shaft and adapted to extend into the casing, an 130 arm extending from the shaft, a weight thereon, a second arm to the shaft, an extension

pivoted to the arm, and a weighted lever pivoted to the side of the draw-head and in the path of said extension.

4. The combination with a draw-head having a transversely-extending recess therein, of a slotted casing detachably secured to the top of the draw-head, ears to the casing, a shaft mounted within the ears, a dog secured to the shaft and normally projecting from the slots, an arm to the shaft, a weight thereon, an arm at the opposite end of the shaft, an extension pivoted thereto, a weighted lever pivoted to the side of the draw-head and normally extending into the path of the extension, a pin having an annular groove adapted to be engaged by the dog, and a rod secured to said pin.

5. The combination with a car, of a draw-head having a transversely-extending recess, a link, a laterally-extending arm thereto, 20 trunnions at the opposite end of said link bearing within the walls of the recess, a rod secured to one of the trunnions, brackets upon the car supporting a rod, a handle to said rod, a lever pivoted to the car, a forked 25 end thereto, and a squared portion to the rod, adapted to be engaged by the fork.

In testimony whereof I affix my signature in presence of two witnesses.

CHRIS E. PAULSON.
